UNITED STATES PATENT OFFICE.

WILLIAM A. SHEPHARD, OF WAUKESHA, WISCONSIN.

SHIP-PROTECTING SHIELD.

1,223,627.

Specification of Letters Patent. Patented Apr. 24, 1917.

Application filed May 29, 1916. Serial No. 100,513.

To all whom it may concern:

Be it known that I, WILLIAM A. SHEPHARD, a citizen of the United States, and resident of Waukesha, in the county of Waukesha 5 and State of Wisconsin, have invented certain new and useful Improvements in Ship-Protecting Shields; and I do hereby declare that the following is a full, clear, and exact description thereof.

10 The present invention has for its object to provide a simple and effective means for protecting vessels of all types against damage by torpedo attacks.

With the above object in view the invention 15 contemplates the embodiment of a submersible shield which may be attached in any suitable manner to the sides of the vessel whereby it can be raised or lowered under suitable winch control.

20 Specific objects of my invention are to provide a shield embodying a frame having a vented sheathing fixed thereto, whereby the speed of the boat is not retarded materially, due to the fact that the water can 25 freely travel through sections or open portions of the shield, while at the same time said shield presents a solid surface for the impact of a torpedo.

20 A further object of my invention is to arrange the shield in such manner that it is suspended by arms from the sides of the boat a sufficient distance whereby a wall of water between the shield and boat will absorb the shock of an explosion caused by 35 the torpedo coming in contact with the shield, it being understood that said shield is free to swing from the point of suspension, but that the resistance offered in case of a torpedo striking it will cause the same to 40 explode.

With the above and minor objects in view, the invention consists in certain peculiarities of construction and combination of parts as herein set forth with reference to 45 the accompanying drawings and subsequently claimed.

In the drawings:

Figure 1 represents a fragmentary sectional view of a vessel showing one side 50 equipped with a shield embodying the features of my invention.

Fig. 2 a plan sectional view of the same, the section being indicated by the line 2—2 of Fig. 1.

55 Fig. 3 a detailed sectional elevation of one

of the shield units, the section being indicated by the line 3—3 of Fig. 1.

Referring by characters to the drawings, *a* represents the side wall of a vessel hull to which is attached by brackets, a series of 60 vertically disposed guide rods 1, the same being shown above the water line. In order to simplify the description and illustration of this invention, only one unit or section of the shield is shown, but it is understood 65 that throughout the length of the vessel a series of such units are employed whereby the ship is protected from end to end, the series of units being arranged to approximately abut each other end to end to form a 70 practically continuous apron.

Each unit of the shield is suspended upon a pair of guide rods 1, by clusters of arms 2, 2', the inner ends of the arms being in pivotal union with heads 3 which are in 75 80 85 90 95 100 110 pivotal union with the guide rods. The outer ends of the arms are each pivoted to ears 3 which project from a back bone 4 that constitutes a frame member, the same being in the form of a rod or tube as shown. The back bone 4 has also a series of spreader brackets 5 depending therefrom, to which brackets are secured vertically disposed sheathing plates 6. As best shown in Figs. 2 and 3, these sheathing plates over lap each other at their edges and are disposed at slight alternating angles in plan, whereby water gaps are formed at their over lapped edges to relieve dead water or drag which would ordinarily occur when the vessel is in motion and traveling in the direction of the arrow, as indicated in Fig. 2. By this construction the outer surfaces of the plates offer an uninterrupted surface to oppose a torpedo traveling toward the sides of the boat and owing to the angular positioning of the plates, the shield unit as a whole will not have a tendency to swing when opposed by the current of water as it travels therethrough.

As shown in Fig. 3 the lower submerged ends of the sheathing plate may be connected by straps 7 whereby rigidity of each unit is insured. It will also be observed that the shield unit as a whole is capable of 105 swinging about its point of suspension which is the back bone or the frame 4. Groups of arms 2, 2' will thus hold the shield units at the desired distance from the side walls of the vessel to provide a body of water 110

therebetween sufficient, to form a cushion to resist the shock of an explosion, incidental to a torpedo coming in contact with the outer surface of the sheathing plate.

5 While I have shown and described a specific form of sheathing plate and means for suspending it from the vessel, it is manifest that I may vary the structural features of the device within the knowledge of skilled mechanics without departing from the 10 spirit of my invention.

When vessels equipped with the protector shields is in no danger of attack, the shield units are adapted to be lifted from their 15 submerged position to overcome all resistance, whereby the ship is not retarded in any manner. In order to lift the shields I provide a power driven winch 8, which is suitably mounted upon the deck of the vessel and the winch is connected to the frame of the shield by a flexible cable or cables 9, the same being shown training over a suitable guide sheave which is fixed to the side of the vessel. By this arrangement it 20 is manifest that under suitable clutch control the winch can be put into motion, whereby the shield units will be lifted from the water and when so lifted their suspending arms will swing upon the heads 25 3 to a vertical position. A further continued movement of the winch, will cause the shield units to ride vertically clear of the water due to the fact that the heads are capable of sliding upwardly upon the guide 30 rods 1.

Hence the shields are folded closely to the sides of the boat and form no obstruction. By this arrangement the shields can be quickly raised and lowered when it is 40 desired, and should a torpedo come in contact with any one of the units, it will explode and thus prevent damage to the side 45 rods 1.

Copies of this patent may be obtained for five cents each, by addressing the "Commissioner of Patents, Washington, D. C."

walls of the vessel. It will be understood of course that when an explosion occurs, the shield unit which causes the torpedo to burst will be more or less damaged, and in order to quickly repair such damage, 45 reserve shield units carried in stock, can be readily put into place whereby the protecting shield as a whole is repaired.

50 It is obvious that in stormy weather in order to prevent the shields from swinging and damaging the sides of the vessel their lower ends may be lashed in any suitable manner to the guide rods or any other point 55 of anchorage that is convenient.

I claim:

1. A submersible shield for protecting ships comprising a frame, vertically disposed sheathing plates carried by the frame having their edges overlapped and spaced apart, arms having ends in hinged connection with the upper portion of the frame means for hingedly connecting the opposite ends of the arms to the sides of the vessel, 65 and means for raising and lowering the shields.

2. A submersible shield for protecting ships comprising a frame, vertically disposed sheathing plates carried thereby having their edges overlapped and spaced apart, arms in pivotal union with the upper portion of the frame, guide rods adapted to be secured to the vessel sides, 70 slidible heads mounted upon the guide rods in pivotal union with the other ends of the arms, a power controlled winch mechanism and cables connecting the winch mechanisms and upper portion of the shield frame.

75 In testimony that I claim the foregoing 80 I have hereunto set my hand at Milwaukee, in the county of Milwaukee and State of Wisconsin.

WILLIAM A. SHEPHARD.
